First Office Action of corresponding Chilean Industrial Design Application No. 201700953 dated Feb. 13, 2018.

Primary Examiner — Karen S Acker

(74) Attorney, Agent, or Firm — Burr & Forman LLP

(57) **CLAIM**

The ornamental design for a nonwoven fabric, as shown and described.

DESCRIPTION

FIG. 1 is a perspective view of a nonwoven fabric, embodying the new design;

FIG. 2 is a top plan view thereof;

FIG. 3 is a rear plan view thereof; and,

FIG. 4 is a cross-sectional view thereof taken along line 4-4 of FIG. 2.

The broken lines shown in the drawings depict portions of the nonwoven fabric that form no part of the claimed design.
